TO THE BONNOT COMPANY, OF CANTON, OHIO, A CORPORATION OF
OHIO.

BRICK RE-PRESSING APPARATUS.

SPECIFICATION forming part of Letters Patent No. 792,999, dated June 20, 1905.

Application filed July 27, 1904. Serial No. 218,346.

To all whom it may concern:

Be it known that we, JOHN O. LUDLAM and CHARLES F. BONNOT, of Canton, Stark county, Ohio, have invented a new and useful Brick 5 Re-Pressing Apparatus, of which the following is a full, clear, and exact description, reference being had to the accompanying drawings, forming part of this specification, in which—

10 Figure 1 is a side elevation, partly in section, showing a preferred form of our apparatus. Fig. 2 is a similar view showing the parts in pressing position, and Fig. 3 is a cross-section on the line III III of Fig. 1.
15 Our invention relates to the re-pressing of bricks or blocks; and it is designed to provide an apparatus which shall be free from shocks and jars, which shall give a large output, improve the quality of the brick, and be 20 a distinct advance mechanically.

The invention consists in providing pressing-plungers which move in the same direction, but at different rates of speed, during the pressing operation, so that the brick is moved 25 bodily during its pressing.

It also consists in pushing the pressed brick or bricks off from the ejecting-plunger and in moving the next brick or bricks to be pressed upon said plunger while the plunger is in motion and is above the level of the top of the mold or that part of the mold that the brick travels over during its motion off the plunger.

The invention further consists in a simple and effective adjustment for one of the plungers, in the bridge arranged to facilitate the passage of the bricks upon the plunger, and in other combinations and details of construction hereinabove described and claimed.

In the drawings, 2 2 represent the lined end 40 plates of the mold, and 3 3 its side plates, the mold being open at the top and bottom to receive the upper plunger 4 and the lower plunger 5. The upper plunger engages suitable guides 6 6 and is pivotally connected to the 45 lower end of a stem 7. This stem is made in two parts having right and left hand screw-threads 8 and 9, respectively, secured within a two-part nut, so that by turning, the throw of the upper plunger may be quickly and

easily regulated. The upper portion of the 50 stem is formed as a part of an eccentric-strap 10, engaging an eccentric 11 or a crank secured to the shaft 12. This shaft is provided with a large gear-wheel 13, intermeshing with a pinion 14 upon the power-shaft 15. 55

The lower plunger 5 is secured to a cross-head 16, extending through the frame of the machine and connected at its ends by suitable pairs of rods 17 with an upper crank-pin 18, actuated by cranks 19, mounted on the shaft 60 12. The rods 17 extend up through the bearings and are provided with springs 20, which as the lower plunger is drawn up during the pressing will accommodate the slightly different amounts of material in the brick without injuring the machine.

At one side of the mold is a receiving-table 21, having a lower reciprocating feeder-head 22, moving in guideways 23 and connected by a central stem 24, which extends up through 70 a slot in the table to a pusher or conveyer 25. We have shown the mold as arranged to press two bricks simultaneously, and in this case the pusher consists of an adjustable base portion with a central forwardly-projecting wing 75 or prong 26, arranged to pass between two bricks. The end of the feeder-head 22 is pivotally connected by links 27 to rock-levers 28, secured to rock-shaft 29. A lever 30, secured to this shaft, carries a roller 31, which moves 80 in a cam-groove 32, formed in a cam-disk 33, bolted to the large gear-wheel 13.

The upper end of the mold-cavity is slightly below the level of the receiving-table, and between the inner end of the table and the end 85 of the mold is a bridge or part of the mold 34, which is curved or convex or beveled upon its upper face, as shown in Figs. 1 and 2. The upper level of this bridge or part of mold is above the highest point of travel of the lower 90 plunger, and its shape allows the brick to lower into the die after passing over the highest point, thus preventing the pusher from moving the brick too far and the upper plunger injuring or clipping it between the upper 95 plunger and mold.

At the end of the mold opposite the feed-table we provide an ordinary continuous-belt

conveyer 35, moving over end pulleys 36, the outer of which is driven by a sprocket-wheel driven by a chain, (indicated at 37.) This chain passes over the sprocket 38 on shaft 39, 5 having a sprocket-wheel 40 with a chain 41, passing over a sprocket-wheel 42 on the power-shaft 15.

In the operation of the machine after the 10 pressing operation the upward movement of both plungers carries the upper plunger away from the pressed brick, while the lower plunger lifts them above the upper edge of the mold-cavity. As the lower plunger reaches a level slightly above this top the pusher begins to 15 move forward, and as it pushes the unpressed bricks forwardly these bricks slide over the bridge and push the pressed bricks forwardly from the top of the lower plunger. During this action this lower plunger is moved first 20 upwardly and then downwardly through its short travel above the top of the mold or above that part of the mold the brick travels over during its motion off the plunger. At the time when the plunger in its reversed and 25 downward movement has reached the level of the die-cavity the unpressed bricks will have pushed the pressed bricks forwardly upon the conveyer, and thus lie in proper position on the plunger. During this ejecting of the 30 pressed bricks and feeding forward of the unpressed bricks the upward and downward travel of the lower plunger causes a slight rocking movement of the bricks. This prevents the sticking of the ends of one set of 35 bricks to those of the next. The pressed bricks as they move onto the conveyer also have a tendency to lift at their forward ends, and thus reduce the friction as they move onto the conveyer. After the unpressed bricks are 40 thus delivered upon the plunger, which continues its downward movement, the pusher is retracted and the upper plunger also moves downwardly. This upper plunger has also been moving through the upper part of its 45 up-and-down stroke during the pushing out of the pressed bricks and pushing in of the unpressed bricks. It moves at a greater rate of speed on its downward stroke than does the lower plunger, and consequently after the 50 lower plunger has been lowered to bring the unpressed bricks wholly within the mold the upper plunger reaches the bricks and the pressing begins. During this pressing the bricks are moving down, and this gives a wiping action upon the inner mold-faces, which improves the quality and appearance of the 55 bricks. At the end of the down travel the pressing is completed, and as the plungers start to move up the upper plunger will move faster 60 and be lifted away from the pressed bricks, so that as the lower plunger rises above the mold-level or above that part of the mold the brick travels over during its motion off the plunger the upper plunger is removed and the pushing 65 operation again begins, as before described.

It will be noted that the plungers are always in motion, traveling at such speed as would be governed by the revolving of an eccentric or crank, the main feature, however, being that the plungers are moving during 70 the pressing operation and the lower plunger is moving during the ejecting operation.

The adjustment of the throw of the upper plunger enables the operator to make the proper adjustment for getting the desired 75 amount of compression upon the brick, and in this case the bricks having ornamental faces the adjustment provides for making this ornamentation as sharp as desired.

We have shown the mold as provided with 80 two cavities separated by a longitudinal partition 43, the plungers being arranged in pairs. The apparatus may, however, be used for pressing a single brick or pressing any number of 85 bricks, as desired.

The advantages of our invention result from improving the quality and increasing the output, owing to the moving of the brick and plungers during the pressing operation, also from the movement of the lower plunger during the act of ejecting the bricks, moving the bricks from the plunger and feeding unpressed bricks thereon while in motion. 90

Many changes may be made in the form and arrangement of the plungers, their actuating connections, the feed mechanism, and other parts without departing from our invention. 95

We claim—

1. In brick-pressing apparatus a mold having opposite open ends, plungers movable within said ends, and means for reciprocating the plungers simultaneously at different rates of speed and in the same direction during the pressing operation; substantially as described. 105

2. In a brick-pressing apparatus, an open-ended mold, an ejecting-plunger, means for moving said plunger beyond the upper end of the mold, or above that part of the mold the brick travels over during its motion off the plunger, and means for moving the pressed 110 bricks from the plunger during its movement beyond the mold end; substantially as described.

3. In brick-pressing apparatus, an open-ended mold having top and bottom plungers, means for reciprocating said plungers, said means being arranged to move the lower plunger upwardly and downwardly beyond the upper end of the mold, or above that part of the mold the brick travels over during its motion off the plunger, and means for pushing unpressed bricks onto said plunger during its movement above the upper end of the mold, or above that part of the mold the brick travels over during its motion off the plunger; 120 substantially as described. 115

4. In brick-pressing apparatus, a mold having open upper and lower ends, plungers arranged to move through said upper end, means 130

for moving the lower plunger upwardly and downwardly above the upper end of the mold, or above that part of the mold the brick travels over during its motion off the plunger, and 5 pusher mechanism arranged to force forwardly unpressed bricks upon the plunger and push off the pressed bricks during the movement of the lower plunger above the upper end of the mold or above that part of the 10 mold the brick travels over during its motion off the plunger; substantially as described.

5. In brick-pressing apparatus, a mold having open ends, opposite plungers movable through said upper end, one of said plungers 15 being movable through a short stroke beyond the end of the mold or above that part of the mold the brick travels over during its motion off the plunger, and mechanism for moving the bricks from said plunger during the said 20 short movement beyond the mold end; substantially as described.

6. In brick-pressing apparatus a mold having opposite open ends, opposite plungers movable through said ends, and actuating connections arranged to move said plungers continuously, said connections being arranged to move the plungers simultaneously in the same direction and at different speeds during the 25 pressing operation; substantially as described.

30 7. In brick-pressing apparatus, a mold having open upper and lower ends, opposite plungers movable through said ends, means for giving the lower plunger a short travel upwardly and downwardly above the upper end 35 of the mold, or above that part of the mold the brick travels over during its motion off the plunger, a bridge or part of mold either curved or beveled at one end of the top of the mold and above its upper edge, and means for 40 pushing bricks forwardly over the bridge during the travel of the lower plunger above the top of the mold; substantially as described.

8. In brick-pressing apparatus, a mold having open upper and lower ends, a bridge at 45 one edge of its upper end, and having a curved or bevel face, reciprocating upper and lower plungers, connections for moving the lower plunger through a short travel beyond one end of the mold and means for pushing bricks 50 over said bridge upon the lower plunger during its travel above the upper end of the mold

or above that part of the mold the brick travels over during its motion off the plunger; substantially as described.

9. In a brick-pressing apparatus, an open 55 mold, opposite plungers movable through the ends of the mold, an actuating two-part stem for one of the plungers, and a nut with reversely-threaded ends uniting the two parts of the stem, whereby the distance between 60 the top and bottom plungers may be regulated, substantially as described.

10. In a brick-pressing apparatus having plungers which are always in motion, and continuously-revolving cranks or eccentrics for 65 actuating said plungers, said cranks or eccentrics governing the travel and speed of said plungers; substantially as described.

11. In brick-pressing apparatus, a mold having open upper and lower ends, opposite 70 plungers movable through said ends, means for moving said plungers simultaneously in the same direction and at a different rate of speed during the pressing operation, means for moving the lower plunger through a short 75 travel above the top of the mold, or above that part of the mold the brick travels over in its motion off the plunger, and means for moving the unpressed bricks upon the top of the lower plunger, and moving off the pressed 80 bricks during this short travel above the top of the mold or above that part of the mold the brick travels over in its motion off the plunger; substantially as described.

12. In brick-pressing apparatus, a mold 85 having opposite open ends, opposite plungers movable within said ends, and means for continuously reciprocating the plungers, said means being arranged to move the plungers simultaneously at a different speed in the same 90 direction during pressing, and to move one plunger beyond the end of the mold during pushing on and off of the bricks; substantially as described.

In testimony whereof we have hereunto set 95 our hands.
